MILES C. HUYETTE, OF BUFFALO, NEW YORK.

DEFLECTING-PLATE FOR SMOKE-FLUES.

1,228,023.

Specification of Letters Patent. Patented May 29, 1917.

Application filed August 23, 1916. Serial No. 116,455.

To all whom it may concern:

Be it known that I, MILES C. HUYETTE, a citizen of the United States of America, residing at Buffalo, county of Erie, and 5 State of New York, have invented certain new and useful Improvements in Deflecting-Plates for Smoke-Flues, of which the following is a full, clear, and exact description.

It is well known to those skilled in the art 10 that it is customary to connect smoke flues to the smoke-stack with a right angle bend and as this connection is at the point where the flue gas temperature is the lowest, objectionable limitations are placed upon the 15 draft through the flue. In view of this it is often necessary to increase the height of the stack in order to overcome the resistance caused by this right angled bend.

I have overcome the disadvantages above 20 enumerated by providing a device which eliminates this sharp right angled connection, thus greatly increasing the strength of the draft by reducing the resistance offered thereto.

25 Moreover, by the use of my invention the height of the smoke-stack may be materially reduced.

Furthermore, I have sought to provide a device which shall be simple and cheap to 30 manufacture and one which may be easily installed.

I have accomplished the advantages above 35 enumerated by the device shown in the accompanying drawings, in which:

Figure 1 is a plan view of the device.

Fig. 2 is a sectional elevation of the same in its normal position.

Fig. 3 is a sectional elevation of the device shown in its lowered position.

40 Fig. 4 is a diagrammatical view of a modified form of my device.

Referring to the drawings and more particularly to Figs. 1 to 3 inclusive, 5 represents a smoke-stack and 6 a smoke flue 45 connected therewith. 7 is my deflecting plate which is disposed within the stack 5 and arranged immediately below the flue 6. The plate comprises a stationary plate member 8 and a movable plate member 9. Each 50 of these plate members are preferably provided at their adjacent edges with hinge parts, through which an operating shaft 10 passes. The stationary plate member 8 is curved upwardly so as to deflect the smoke 55 and gases coming from the flue 6 and direct their path up the stack without adding

greatly to the resistance of flow. The movable plate member 9 is curved at its inner edge to coincide with the curvature of the stationary plate member and has its remaining part preferably bent downwardly and outwardly so as to form a pocket 13 for the accumulation of soot. The operating shaft 10 passes through the stack 5 and is pivotally disposed within the hinge part of the 60 stationary plate member 8. The hinge part of the movable plate member 9 is rigidly secured to the operating shaft 10 so that when the shaft is rotated the movable plate member 9 may be rotated therewith. Rigidly 65 disposed on the outer end of the operating shaft 10 is an operating arm 11. Mounted upon this arm is a counter weight 12 which is so proportioned and adjusted that the movable plate member 9 is normally held in 70 the position shown in Fig. 2. In Figs. 2 and 3 the operating arm 11 and counter weight 12 are shown in broken lines because they are disposed upon the part of the stack which, in these sectional views, is removed. 75

In Fig. 4, where I show a modified form 80 of my device, the movable plate member 14 is preferably curved so that it has the same radius as the stationary plate member 8 and is not provided with the soot 85 pocket as is the form shown in the other figures.

It will be clearly seen that, when my device is installed, the products of combustion coming from the smoke flue 6 (in the direction of the arrows in Fig. 2) will strike the curved plate members and be deflected upwardly through the stack thereby eliminating the friction common in right angled connections. All the soot which accumulates in the stack and upon the stationary 90 plate member 8 will fall on to the plate member 9 and into the soot pocket 13 thereof. At any time that this accumulation becomes excessive, the operating arm 95 may be raised which will move the plate member 9 to the position shown in Fig. 3 where the soot will be dumped from the pocket 13.

It is obvious that, while my device is 100 shown in connection with a round stack, it may be used with equal efficiency with a stack of any other shape. Furthermore, if desired, the stationary plate member 8 and the movable plate member 9 may be made 105 integral or rigidly connected so that both will operate when the operating shaft 10 is 110

rotated. These and other modifications of the details herein shown and described may be made without departing from the spirit of my invention or the scope of the appended claims and I do not, therefore, wish to be limited to the exact embodiment herein shown and described.

Having thus described my invention, what I claim is:

- 10 1. The combination with a smoke-stack and a smoke flue of a deflecting plate, said plate comprising a stationary plate member and a movable plate member, and means for controlling said movable plate member.
- 15 2. The combination with a smoke-stack and a smoke flue of a deflecting plate, said plate comprising a stationary plate member and a movable plate member, an operating shaft passing through the stack and connected with the adjacent ends of said plate members, and means for keeping said shaft and said movable plate members in their normal positions.
- 20 3. The combination with a smoke-stack and a smoke flue of a deflecting plate, said plate comprising a stationary plate member and a movable plate member, and an operating shaft passing through the stack and pivotally mounted therein, said shaft being rig-

idly connected to said movable plate member.

4. The combination with a smoke-stack and a smoke flue of a deflecting plate, said plate comprising a stationary plate member and a movable plate member, said movable plate member being provided with a pocket for the accumulation of soot, and means for operating said movable plate member, whereby the soot may be dumped therefrom.

5. The combination with a smoke-stack and a smoke flue of a deflecting plate, said plate comprising a stationary plate member and a movable plate member, an operating shaft passing through the stack and pivotally mounted therein, said shaft being rigidly connected to said movable plate member, an operating arm secured to said shaft, and a counter weight adjustably mounted upon said arm, whereby said movable plate member may be operated.

In testimony whereof, I have hereunto signed my name in the presence of two subscribing witnesses.

MILES C. HUYETTE.
